UNITED STATES PATENT OFFICE

2,160,665

TRANSFER

Joseph Linderman, Chicago, Ill.

Application August 26, 1937, Serial No. 160,957

1 Claim. (Cl. 283—27)

This invention relates to transfers for street cars, busses, elevated, subways and the like.

One of the objects of my invention is to provide a transfer with an inclined end which serves to indicate the direction of travel to the end that the conductor can readily observe whether a proper transfer is handed to him.

Another object of my invention is to provide a transfer in which the time designations are printed around the border edge of the transfer so that one punch will indicate the hour, minute as well as the A. M. or P. M. and further that when said transfer is positioned on top of those retained in the hand of the conductor he can tell by comparing the position of the punch in that transfer with the position of the punch of the transfers he holds in his hand as to whether an improper amount of time has transpired.

Another object of my invention is to provide a transfer which can be examined by the conductor in a minimum of time and with a minimum possibility of error.

Another object of my invention is to provide a transfer which eliminates the necessity of making a number of punches by the conductor issuing the same.

Another object of my invention is to provide a transfer whereby the time period and the direction of travel can be readily ascertained without a reading of the transfer.

Another object is to provide a transfer in which the edges of the transfer will not register when the transfer is folded upon itself, thereby facilitating the rapid unfolding thereof.

Other objects will become apparent as this description progresses.

It is well known that with the present conventional transfer a considerable amount of time is lost by the conductor in examining and inspecting the transfers that are handed to him due to the fact that he first must inspect the punch hole indicating the direction of travel and also the separate holes indicating the hour, minute and the A. M. or P. M. thus requiring him to examine approximately five different punched places. This causes considerable delay, particularly at tramway intersections where a number of transfers must be inspected before the car can proceed, all of which causes a slowing down in the service of the transportation company. Furthermore it is impossible to accurately check the transfers in the allotted time and consequently considerable fraud is perpetrated upon the transportation companies by passing off to them obsolete transfers, which, due to the lack of time and inability to in-

spect by the conductors, causes a loss of an inestimable amount of money. Furthermore the necessity of requiring each conductor issuing a transfer to punch five or six different places results in a loss of time and diverts the conductor's attention from the passengers on the platform and on the platform step. However with my invention all of the objectionable features attendant present day transfers are obviated.

In the drawing, Figure 1 is a view of my transfer showing the inclined end on the right side of the transfer with the greatest width at the bottom.

Figure 2 is a view of my transfer showing the inclined end on the right side with the greatest width at the top.

Figure 3 is a view of my transfer showing the inclined end on the left side with the greatest width at the bottom.

Figure 4 is a view of my transfer showing the inclined end on the left side with the greatest width at the top.

Figure 5 is a view on a reduced scale showing the transfer folded upon itself.

Referring to the drawing it will be seen that all the transfers are similar in size and shape, except that by virtue of the printing upon the face of the transfer the inclined ends are directed in different positions. Since all of the transfers are printed substantially alike a description of one will be sufficient.

Referring specifically to Figure 1, I provide a substantially rectangular shaped transfer having three separate straight edges 10, 11, and 12 and an inclined end edge 13. Printed along the longitudinally straight edges 10 and 12 in a clockwise direction are the hourly time designations 5 to 12 inclusive, which are designated by heavy black lines and which are further subdivided into ten minute periods by lighter lines. It will be noted that the numerals are printed so that they all face outwardly. On the straight edged side 11 and the inclined edge 13 of the transfer and continuing in clockwise direction are the time designations 1 to 4 inclusive, divided and subdivided in the same manner as those on the longitudinal edges. It will be noted that on the upper left hand side of the transfers the letters P. M. are placed so that beginning with the numeral 1 on the lower left side of the edge and continuing to number 12 on the longitudinal edge the time period would be a P. M. period. While on the lower right hand corner is placed the time designations A. M. to indicate such period for the

numerals on the inclined edge 13 and the longitudinal edge 10.

On the upper right hand corner of the transfer is placed the designation "half fare" which can 5 be punched if the transfer is issued for a half fare. Adjacent the numerals on the inclined edge I place the designation of the direction of travel. The direction shown in Figure 1 being eastbound, while in the other transfers in Figures 2, 3, and 4 10 are printed the other directions of travel.

In the Figures 2, 3, and 4 it will be noted that the time designations are printed in substantially the same manner as in Figure 1 except that in the various illustrations shown the normal position 15 of the transfer is such that the inclined edge is inclined in different directions. By having the inclined edges in this manner, each inclined edge represents a different direction of travel so that the conductor can by looking at the 20 inclined edges determine whether the proper transfer has been handed to him without the necessity of reading the inscription to so determine. It will readily be observed from the transfer that by making one punch hole, as shown in 25 Figure 1, that the hour, minute as well as the A. M. or P. M. is thus designated. In the drawing shown in Figure 1 the punch is indicated at 50 minutes after 8 P. M. whereas if the punch were on the opposite side of the transfer it would 30 be 50 minutes after 8 A. M. It will be obvious that as the conductor places one transfer over those that he holds in his hands that the openings should substantially register and if there is any considerable spacing in the punched opening 35 between the transfer handed to him and those he is holding in his hand, his attention is promptly called to the fact that the transfer is overdue. Furthermore that by receiving the transfer with the inclined edges on one end he can tell at a

glance the direction of travel to which the passenger is entitled to transfer and by placing such transfer on the pack of transfers he is holding in his hand his attention is readily called to the fact that an improper transfer is handed to him 5 if the edges do not coincide, thus obviating the necessity of closely examining each transfer as it is handed to him.

Furthermore in a majority of instances the passenger has a tendency to fold the transfer up 10 on itself so that the edges will register and when first handing it to the conductor he tries to unfold it, causing a considerable delay in time and retarding service. However, with my invention the edges will not register end to end (see Fig. 15 15) when the transfer is folded thus making it very easy for the passenger or the conductor to unfold the transfer in a minimum of time with little effort. Further with my invention practically all necessity for close inspection of the 20 transfer is eliminated as is also the necessity of making a number of punches by the conductor issuing the transfer.

What I desire to secure by Letters Patent is:

In a series of transfers, certain of said transfers 25 of said series indicating one direction of travel, other transfers indicating other directions of travel, each of said transfers having an oblique end and printed matter on the face of said transfer indicating a definite direction of travel 30 for said transfer, said transfer and printed matter thereon being so arranged relative to the oblique end that when held in reading position, transfers indicating the same direction of travel will when superposed have their oblique ends in 35 registry and a transfer indicating a different direction of travel will not have its oblique end in registry.

JOSEPH LINDERMAN.
